UNITED STATES PATENT OFFICE.

JAMES F. McELROY, OF ALBANY, NEW YORK, ASSIGNOR TO CONSOLIDATED CAR-HEATING COMPANY, A CORPORATION OF WEST VIRGINIA.

ELECTROMAGNETIC VALVE-CONTROLLER.

1,198,737.

Specification of Letters Patent. Patented Sept. 19, 1916.

Application filed May 9, 1914. Serial No. 837,562.

To all whom it may concern:

Be it known that I, JAMES F. McELROY, a citizen of the United States, residing at Albany, county of Albany, State of New 5 York, have invented certain new and useful Improvements in Electromagnetic Valve-Controllers, the following being a full, clear, and exact disclosure of the one form of my invention which I at present deem preferable.

For a detailed description of the present form of my invention, reference may be had to the following specification and to the accompanying drawings, which illustrate my 15 invention, wherein—

Figure 1 shows my apparatus in connection with a pneumatic door-engine controlled thereby; Fig. 2 shows my apparatus in perspective; Fig. 3 shows the valves and 20 their operating mechanism.

My invention relates to electromagnetic valve-controllers and particularly to a reversing valve for controlling the ports of a pressure-fluid engine.

The object of my invention is to enable me to make use of valves of the needle type, which are not subject to the wear incident to valves of other types, and also to operate such needle valves by means of open-circuit 25 magnets. For this purpose I provide in the reverser two valves of the needle type, but, instead of operating them directly by the magnets, I operate them by means of a spring which the magnets control. For this 30 purpose I interpose certain setting means by which the spring may be set to act upon the two valves alternately, and I place the said setting means under the control of the magnets. By this means I am able to secure a 35 more reliable operation and am also able to use open-circuit magnets which may be operated by circuit-closers located at a number of different points.

Turning to Fig. 1 of the drawing, A represents my reverser and B represents a pneumatic door-engine controlled thereby, the door-engine being arranged to operate the sliding door C of a railway car.

The external appearance of my electromagnetic reverser is shown in Fig. 2, consisting fundamentally of two tubular thimble-shaped casings D and D¹ which are of magnetic material and each of which contains the coils of a solenoid form of magnet.

S represents the core of the said solenoid 55 which is reciprocated to and fro according as one or the other of the two magnet coils is energized. F¹ represents an inlet pipe leading from a suitable source of pressure supply, such as the auxiliary air tank of the 60 pneumatic brake apparatus. F² represents outlet pipes leading from the reverser to two different door-engine cylinders; each pipe supplying one of such cylinders. F³ is the exhaust pipe. E represents a casting 65 secured between the tubular casings D and D¹, and serving to carry the various pipes leading to and from the reverser, and also to carry the two valve-chambers and valves by which each of the pipes F² leading to the 70 engine cylinder may be connected either to the supply pipe F¹ or to the exhaust F³.

Fig. 3 shows a portion of the inner side of the aforesaid plate E, and the two valve-chambers carried thereby. These valve-chambers are formed in the casting E, and appear externally as semi-cylindrical projections from the inner surface of the casting E. One of these valve-chambers is shown in section, the other being shown as 80 it appears from the outside. The construction of both chambers being the same, but one is described in detail. As is shown in the sectional view, the lower end of the chamber E¹ is closed at the bottom by a 85 screw plug e¹. In a recess in this screw plug e¹ is seated a coil spring G which carries the needle-valve and forces it upward, bearing against disk h¹ on the valve-stem H. Just above the disk h¹ is a conical valve surface 90 h² which, when forced upward by the spring G, serves to close the passageway between the chamber E¹ (into which the pipe F¹ delivers air from the supply reservoir) and a chamber E² which communicates with the 95 pipe F² leading to the engine cylinder. The valve stem H is provided at its upper end with an enlarged extension H¹ which serves as an operating pin for the valve stem. The lower end of this operating pin H¹ is of a 100 conical shape and forms a valve surface h³ which, when the pin H¹ is pressed downward, closes the passageway between the aforesaid chamber E² and the chamber which connects with the exhaust pipe F³.

It will be manifest that, when the valve-stem H is pressed upward by the spring G, the chamber E², which communicates with the

pipe F^2 leading to the engine cylinder, will be shut off by the valve surface h^2 from the chamber E^1 which contains the air-pressure supply but will be connected, by the lifting 5 of valve-surface h^3 , with the exhaust chamber. On the other hand, when the valve-stem H is pressed downward the valve-surface h^2 will act to open the connection between the aforesaid pressure-supply chamber 10 E^1 and the pipe F^2 leading to the engine cylinder. At the same time the downward movement of the stem H will bring the valve-surface h^3 against the opening leading from the chamber E^2 to the exhaust, thereby 15 shutting off the exhaust chamber from the engine cylinder pipe F^2 . The other valve will be identical with the one I have just described and will be similarly operated by means of a corresponding pin H^2 . 20 A rocker J is pivoted at a point midway between the two valve-pins H^1 and H^2 and projects across the upper end of each of the said pins. According as one end or the other of this rocker is depressed it will 25 come into contact with the pin H^1 or the pin H^2 and, by pressing down upon it will operate the corresponding valve against the upward force of spring G . It will thus appear that each valve is provided with an operating spring G serving to actuate it in one direction, its operation in the opposite direction being produced by the downward pressure of one end of the rocker J . 30 Instead of operating each of the two 35 valves above described directly by the magnet, I provide therefor an operating spring K , which is considerably stronger than the spring G . I, moreover, arrange setting means by which the force of the spring K 40 may be applied to either one of the valve pins H^1 or H^2 alternately. This setting means comprises a vertical link L provided with an offset at its upper end upon which is mounted a roller l which bears upon the 45 upper surface of the rocker J . The upper surface of the rocker is somewhat curved so that, as the roller l moves to one end or the other of the rocker, it will roll down the incline of the said curved upper surface, and 50 remain set or retained in position on whichever end of the rocker it may come. The lower end of the link L is jointed to the horizontal arm P of the bell crank lever by means of a pin p . Said bell crank lever is 55 pivotally supported by a stationary part of the apparatus, and the arm P_1 thereof is connected to one end of the aforesaid spring K , the other end of the spring being adjustably anchored to some stationary part of the apparatus. Near the middle of the link L is jointed a shorter link R , the right-hand end of the link R being jointed to the link L , and the left-hand end being jointed to the solenoid core S . The solenoid core is 60 adapted to be moved in one direction by the 65

coil T^1 and in the opposite direction by the coil T^2 . Each of these coils is contained in a separate normally-open branch circuit between the trolley and the ground or between the terminals of any other suitable 70 source of electromotive force. The circuit of coil T^1 may be closed at any time by pressure on the circuit-closer button W^1 , while the circuit of the magnet T^2 may be similarly closed by the circuit-closer button W^2 . 75

The operation of the device is as follows: Assuming the parts to be in the relative positions shown in Fig. 3, the roller l will rest on the left-hand end of the rocker J and the link L which carries the said roller will be 80 drawn downwardly by means of the spring K acting on the said link through the angle-lever P , P^1 . That is to say, the tension of the spring will be exerted toward the left on the lever arm P^1 , tending thereby to turn 85 the lever arm P downward and cause it to draw down upon the link L . The pressure of the link L and its roller l will force the left-hand end of rocker J down, thereby depressing the valve-pin H^2 , closing the exhaust connection and opening the supply 90 connection of the engine cylinder pipe F^2 which is controlled by that valve. At the same time the right-hand end of the rocker J will be raised, thereby releasing the valve 95 stem H of that valve which will be moved upward by its spring G to open the exhaust connection and close the supply connection of the engine cylinder pipe F^2 corresponding to that valve. It will be understood that 100 the link and its roller l have been brought to the left-hand position shown in Fig. 3 by the pulling action of the coil T^1 on the solenoid core S and the short link R . With the parts in the position just described, air 105 pressure will be admitted to one engine cylinder—say the cylinder which serves to close the door C , the other cylinder being then connected to the exhaust. Since the link L is set or retained in this position, it will not move back, when the circuit of coil T is again 110 broken, but will remain as it has been set by the said coil. On the other hand, when it is desired to open the door, the button W^2 115 will be pressed momentarily, thereby energizing the coil T^2 which will draw the core S to the right, thereby causing the link R to throw the link L and its roller l to the right-hand end of the rocker J , the movement of 120 said link L being upon the pivot p , the tension of spring K serving to practically prevent any movement of the bell crank lever. This movement of link L will reverse the valve connections, depressing pin H^1 and valve h^2 of the right hand chamber E^1 , and the engine-cylinder which was formerly connected to exhaust will receive air pressure, while the other cylinder, which formerly received air pressure, will be connected 125 to the exhaust. The relative positions of 130

the links R and L remain practically unchanged, the jointed connections of the link R serving to prevent binding of the parts during their movement. It will be observed that since the parts will remain set in one direction or the other, it requires only a momentary closure of one of the magnet coils to put the apparatus in either one of its two operating positions. The pivotal point 5 of the rocker J constitutes a dead center and the spring by acting upon one side or the other of this dead center causes the operation of the two valves alternately in the manner above described.

15 What I claim as new and desire to secure by Letters Patent is:

1. In an electric reverser, the combination with two valves each controlling inlet and outlet ports, a rocker member to selectively move either of said valves, electromagnetic means engaging said rocker member and movable relatively thereto to actuate the same, and means for constantly maintaining a yielding pressure upon said rocker member.

2. In an electric reverser, the combination with two valves each controlling inlet and outlet ports, a rocker member to selectively move either of said valves, a pivoted actuator for engaging said rocker member and movable relatively thereto to actuate the same, means for constantly maintaining a yielding tension upon said actuator, and electromagnetic means for operating said actuator.

3. In an electric reverser, the combination with two valves each controlling inlet and outlet ports, of independent valve springs therefor, each actuating its valve in one direction, a rocker member engaging said valves to selectively move them in opposition to said springs, an actuator engaging said rocker member and movable relatively thereto, electromagnetic means for shifting said actuator, and a single spring for constantly maintaining a yielding tension upon said actuator.

4. In an electric reverser, the combination with two valves each controlling inlet and outlet ports, a rocker member engaging said valves to selectively move either of them, an actuator engaging said rocker member and movable relatively thereto, two magnets for moving said actuator in opposite directions, normally open circuits for the respective magnets, and circuit closers for the respective circuits.

5. In an electric reverser, the combination with two valves, a rocker member engaging said valves to selectively move either of them, an actuator supported and movable independently of said rocker member and having a portion overhanging and engaging said rocker member to actuate the same, electromagnetic means for operating said

actuator, and means for constantly maintaining a yielding tension upon said actuator.

6. In an electromagnetic valve-controller, the combination with a valve, and a spring 70 for actuating the valve in one direction, a rocker member for moving the valve in the other direction, a dead-centered actuator for said rocker member movable independently of and relatively to said rocker member, 75 means for constantly maintaining a yielding tension upon said actuator, and electromagnetic means for imparting movements to said actuator.

7. An electromagnetic valve controller 80 comprising a valve, a spring for actuating the valve in one direction, a pivoted rocker member for moving the valve in the other direction, a pivoted actuator movable relatively to the rocker member, electromagnetic 85 means for imparting pivotal movement to the actuator, and means for constantly maintaining a yielding tension upon said actuator.

8. An electromagnetic valve controller 90 comprising a valve, a spring for actuating the valve in one direction, a pivoted rocker member for moving the valve in the other direction, a pivoted actuator movable relatively to the rocker member and having a 95 portion in frictional engagement with the rocker member, electromagnetic means for imparting pivotal movement to the actuator, and a spring connected with the actuator to maintain a constant yielding tension there- 100 upon.

9. An electromagnetic valve controller comprising a valve, a spring for actuating the valve in one direction, a pivoted rocker member for moving the valve in the other direction, a bell crank lever, an actuator pivotally supported by said bell crank lever and having a portion in frictional engagement with said rocker member, electromagnetic 105 means for imparting pivotal movement to the actuator, and means connected with said bell crank lever for maintaining a constant yielding tension upon said actuator.

10. An electromagnetic valve controller 115 comprising a valve, a spring for actuating the valve in one direction, a pivoted rocker member for moving the valve in the other direction, an actuator movable independently of the rocker member and having a 120 roller engaging said rocker member, electromagnetic means for imparting pivotal movement to said actuator, and means for maintaining a constant yielding tension upon said actuator.

11. An electromagnetic valve controller comprising a valve, a spring for actuating the valve in one direction, a pivoted rocker member for moving the valve in the other direction, a bell crank lever, an actuator 130

4

pivottally supported by said bell crank lever and having a roller engaging said rocker member, electromagnetic means for imparting pivotal movement to the actuator, and a 5 spring connected with the bell crank lever for maintaining a constant tension upon said actuator.

12. An electromagnetic valve controller comprising a valve, a spring for actuating 10 the valve in one direction, a pivoted rocker member for moving the valve in the other direction, an actuator having movable engagement with said rocker member, a core connected with said actuator, electromagnetic 15 means for shifting said core longitudinally, and means for maintaining a constant yieldable tension upon said actuator.

13. An electromagnetic valve controller comprising a valve, a spring for actuating 20 the valve in one direction, a pivoted rocker member for moving the valve in the other direction, an actuator having movable engagement with said rocker member, spaced apart magnets, a single core for both magnets, a link pivotally connected with the core and with the actuator, and means for maintaining a constant yieldable tension upon 25 said actuator.

In witness whereof I have hereunto set 30 my hand, before two subscribing witnesses this 6th day of May, 1914.

JAMES F. McELROY.
